US0D1106618S

(12) **United States Design Patent** (10) **Patent No.:** **US D1,106,618 S**
(45) **Date of Patent:** **** Dec. 16, 2025**

(54) **PET TRAINING CLICKER**

(71) Applicant: **Dongguan Fengsheng Pet Products Co., Ltd**, Guangdong (CN)

(72) Inventor: **Jiefeng Li**, Jiangxi (CN)

(**) Term: **15 Years**

(21) Appl. No.: **29/969,032**

(22) Filed: **Oct. 21, 2024**

(51) LOC (15) Cl. **30-99**

(52) U.S. Cl.

CLAIM

The ornamental design for a pet training clicker, as shown and described.

DESCRIPTION

FIG. 1 is a front, left, top perspective view of a pet training clicker, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The dashed broken lines in the figures are for the purposes of illustrating portions of the pet training clicker and form no part of the claimed design.

1 Claim, 8 Drawing Sheets
